UNITED STATES PATENT OFFICE.

FLOREN A. MORRIS, OF ALLIANCE, OHIO.

DESIGN FOR A GRAVE-MARKER.

No. 40,110.

Specification for Design.

Patented June 29, 1909.

Application filed May 11, 1909. Serial No. 495,371. Term of patent 3½ years.

To all whom it may concern:

Be it known that I, FLOREN A. MORRIS, a citizen of the United States, residing at Alliance, in the county of Stark and State of Ohio, have invented a new, original, and ornamental Design for a Grave-Marker, of which the following is a specification, reference being had to the accompanying drawings, forming part thereof.

The figure is an elevation of a grave marker, showing my design.

I claim:

The ornamental design for a grave marker, as shown.

FLOREN A. MORRIS.
